GUN MOUNT

Joseph M. Colby, United States Army,
Lake Mills, Iowa

Application July 1, 1942, Serial No. 449,302

1 Claim. (Cl. 89—41)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a periscope sight for a gun and its mounting thereto.

An object of the invention is to provide a periscope gun sight coordinated with a gun mount through a simple adjustable coupling.

Another object of the invention is to provide a demountable optical system in axial alignment with the trunnions of a gun mount.

A further object of the invention is to provide a protected aiming system which incorporates wide angle vision and oscillates with a gun mount.

Other objects and advantages will be apparent during the course of the following description, in which:

Fig. 1 is a diagrammatic plan view of a gun mount and the coaxing periscope sight system behind a section of armor plate.

Fig. 2 is an enlarged sectional view of the coupling between the sight and the gun trunnion.

Fig. 3 is a front elevation of one of the locking plates.

Fig. 4 is a front elevation of another of the locking plates.

Fig. 5 is a perspective view of the adjusting pin.

Fig. 6 is a view on the line 6—6 of Fig. 2.

Fig. 7 is a side elevation with parts in section of a periscope sight in an observation housing of an armored device, and

Fig. 8 is an elevational view with a part in section showing a periscope sight mounted in the top of an armored device.

A gun 1 is mounted in an armored device on suitable trunnions 2 resting in bearings 3. One of the trunnions carries an extension 4 which is splined for a short distance at 5 as shown in Fig. 2. A circular disk 6 having a central aperture 7 shaped to conform to the splines 5 is pressed into locking engagement with the extension 4.

A periscope housing 8 is rotatably mounted on shafts 9 journaled in conventional bearings 10. The shaft 9 nearest the gun 1 projects through its bearing and carries splineways 11, see Fig. 2. A plate or disk 12 with a notched central aperture 13 is press fitted on the splined shaft 9.

The shafts 9 of the periscope housing 8 and the gun trunnions 2 are in coaxial alignment and are adapted to be coupled together through the disks 6 and 12. Disk 12 is pierced by an elongated arcuate slot 14 as shown in Fig. 3. Dia- metrically opposite slot 14 is a cylindrical recess 15 which faces the adjoining disk 6. In disk 6

opposite the slot 14 in disk 12 is a threaded bore 16. Diametrically opposite bore 16 on disk 6 is a circular aperture 17. A threaded bolt 18 slips through the slot 14 in disk 12 and engages the internally threaded bore 16 in disk 6 as shown in Fig. 2. When tightened this bolt 18 locks the two disks together so that the gun 1 and sight housing 8 move simultaneously. In Fig. 2 the adjoining disk faces are shown slightly separated for purposes of illustration.

A periscope 19 which includes a 45° mirror system and an aiming telescope 20 having a cross wire is demountably engaged by the housing 8 as shown in Fig. 7. The mirrors 36—36' are so disposed that a ray of light passes through the periscope 19 as indicated by the dash-dot line. The optical system 19 must be collimated with the axis of the gun 1. Final angular adjustments are made with the adjusting pin 21 shown in Figs. 2 and 5. Pin 21 has a circular head 22 eccentrically mounted on one end of the shank 23 and a knurled or tool-engaging portion 24 at the opposite end. The eccentric head 22 engages in the recess 15 in plate 12 and the shank 23 passes through the smooth bore 17 in plate 6. When the locking bolt 18 is loosened and the pin 21 rotated by using a tool on portion 24, the plate 12 is displaced angularly about its axis with respect to plate 6 because of the eccentric. Elongated slot 14 permits a limited amount of relative movement. When the gun and periscope are accurately collimated, the bolt 18 is tightened to lock the devices in the adjusted position.

Fig. 7 illustrates one manner in which the periscope sight 19 may be mounted in a housing 8. Housing 8 is an armored rotor carried by the shafts 9 in the bearings 10. The periscope slides into the vertical portion 25 of the indirect light passage and is urged into position by spring 40 pressed detents 26. A spring pressed plunger 27 locks in a recess 28 in the periscope to hold it securely in position. A lever 29 engages the plunger and pressure on the handle portion 30 will rotate it clockwise about a pivot 31 to release the plunger. A tug on the handle 32 will remove the periscope from its operative position.

The rotor 8 has an upper sight passage 33 which can be presented to an observation aperture 34 in the armored wall 35 of a device. Behind the frangible upper mirror 36 of the periscope 19 is a chamber 37 having a curved wall 38 for reversing the direction of and eliminating projectiles which fracture the mirror 36. When the mirror is broken, the rotor is moved counterclockwise 55 until the hood 39 seals the observation aperture

34 whereupon the periscope can be removed without exposing the observer to gunfire and a new reflector can be safely inserted. The rotor may then be indexed to the viewing position shown in Fig. 7.

In some types of devices the protective hood 39 and the ricocheting wall 38 are not employed and a projectile passes through the reflector 36 and over the top of the device. Fig. 8 illustrates a periscope sight 19 mounted for oscillation in a rotor 40 about an axis 41 in the armored top 42 of a device. Protection against projectiles which might strike an end of sight 19 is accomplished by employing a vertical plate 43 on each end of the observation slit.

This sighting system when combined with guns of certain sizes is adapted for use in several types of tanks. The periscope permits protected indirect vision and also aiming of the gun. The coaxial mounting of the oscillating members and the eccentric adjusting feature provide an observation and aiming system which is simple in construction, accurate within the range of tank operations, rugged, and durable. This gun mount permits the physical separation of the gun pointing personnel from the moving elements of the

gun, and places the eyes of the gunner on the approximate trunnion axis of the gun. This permits placing the gunner in a secure and comfortable fixed seat, permitting him to follow elevation or depression of the gun by simple movements of his head.

The embodiment herein disclosed is merely illustrative and may be departed from in many ways without departing from the spirit and scope of the invention as pointed out in and limited solely by the appended claim.

I claim:

In combination, a gun mounted for elevation about a horizontal axis, a shaft extending from the gun in coaxial relation with said axis, another shaft adjacent to and coaxial with the first shaft, a periscope sight carried by the second shaft, plates secured respectively to said shafts in juxtaposition, a stem rotatably mounted in one of said plates, an eccentric carried by said stem and received in the other plate to adjust the position of one plate relative to the other, and releasable means for locking said plates together in the adjusted position.

JOSEPH M. COLEY.
